(57) **CLAIM**

The ornamental design for a vanity mirror, as shown and described.

DESCRIPTION

FIG. 1 is a top, front, left-side perspective view of a vanity mirror embodying our design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a bottom plan view thereof; and,

FIG. 7 is a top plan view thereof.

The vanity mirror is shown with a symbolic break in its length, represented by break lines. The appearance of any portion of the article between the break lines forms no part of the claimed design.

The broken lines shown are included for the purpose of illustrating portions of the vanity mirror that form no part of the claimed design.
